Inventor

P. J. MCKEE,

By Clarence A. O'Brien.

Attorney

UNITED STATES PATENT OFFICE.

PATRICK J. MCKEE, OF DEER LODGE, MONTANA.

SUPPORT FOR AIR-RETAINER VALVES.

Application filed March 1, 1926. Serial No. 91,644.

The present invention relates to a support which is adapted particularly for use in connection with the air retainer valves which are associated with railway cars.

The air retainer valves now generally in use are constructed of cast iron material and oftentimes whenever it becomes necessary to remove the valve from the car for cleaning or repairing purposes, considerable difficulty is experienced, and as a result, the attaching lugs which are associated with the valve will become broken off, thus rendering the valve useless.

One of the important objects of the present invention is to provide a support whereby the retainer valves which have their lugs broken off may be reused and supported in proper position on the railway car, thus saving considerable expense and eliminating unnecessary waste.

A further object is to provide a support for air retainer valves of the above mentioned character which provides a permanent fixture and includes a means for detachably clamping the retainer valve in position so as to enable said valve to be readily and easily removed for cleaning or repairing purposes without any injury being sustained.

A still further object is to provide a support of the above mentioned character which is simple in construction, inexpensive, strong, and durable and further well adapted to the purpose for which it is designed.

Other objects and advantages of the invention will become apparent during the course of the following description taken in connection with the accompanying drawing.

In the accompanying drawing forming a part of this application, and in which like numerals designate like parts throughout the several views:

Figure 1 is a side elevation of the support embodying my invention showing the same in use.

Figure 2 is an end elevation of the support, and

Figure 3 is a fragmentary sectional view approximately on line 3—3 of Figure 2 looking in the direction of the arrows.

In the drawing, wherein for the purpose of illustration is shown the preferred embodiment of my invention, the numeral 1 designates generally an air retainer valve of the double pressure type and as the same is well known in the art, and as said valve further forms no important part of the pres-

ent invention, a detailed description thereof is thought unnecessary. It is of course to be understood that the invention may be equally as well employed in connection with air retainer valves of the single pressure type.

The usual hexagonal nut which forms a part of the valve 1 and affords a means for connecting the valve with the pipe 2 is indicated at 3. These air retainer valves are constructed of cast iron material and are ordinarily provided with laterally extending lugs to facilitate the attachment of the valves on the under side of a railway car in the manner also well known in the art.

Whenever it becomes necessary to remove the retainer valve in order that the same may be cleaned or repaired, it has been found necessary to employ a crow bar or the like, and as the result of the use of such implement, the attaching lugs of the air retainer valves will accidentally break off as is indicated at 4 in the drawing. An air retainer valve which has its attaching lugs broken off is rendered useless and as a result becomes waste material and must be replaced by a new valve, thus entailing considerable cost and expense. For the purpose of overcoming the unnecessary waste of air retainer valves which have their lugs broken off, I have provided a highly novel, yet simple support for permitting such valves to be again placed in use after the same have been repaired or cleaned.

My improved support comprises a bracket designated generally by the numeral 5 and this bracket includes a flat strip of metal which is bent at points adjacent its ends as indicated at 6 so that the intermediate portion 7 of said strip is spaced from the portion of the railway car to which the ends of the strip of the bracket 5 are secured by appropriate fastening means illustrated at 8. This bracket 5 is preferably secured to the car at a point adjacent the hexagonal shaped head 3 which forms a part of the air retainer valve 1.

The support further includes the clamp 9 which is constructed of flexible sheet metal material, and the intermediate portion of the strip of metal forming the clamp 9 is provided with the laterally extending ears or wings 10 which extend on the opposite sides of the strips and these extensions are bent around the side edges of the intermediate portion 7 of the bracket 5 and the free ends

of these extensions abut the inner face of the intermediate portion 7 of the bracket 5 and also abut with each other. A rivet 11 affords a means whereby the intermediate portion 5 of the strip forming the clamp 9 may be secured to the intermediate portion 7 of the bracket 5 and this construction is also clearly illustrated in Figure 3. The provision of the laterally extending ears or wings 10 on the intermediate portion of the clamp 9 will afford a rigid connection between the clamp and the bracket. The free end portions of the strip forming the clamping member 9 are so bent as to fit snugly around the sides of the hexagonal shaped member 3 which is associated with the air retainer valve 1 and the free ends of the strips comprising the clamping member 9 are disposed laterally in spaced relation beyond one of the sides of the hexagonal shaped member 3 and one of the free ends of the strips is bent downwardly for a purpose to be presently described.

A bolt 12 extends through a pair of registering openings provided in the laterally disposed ends of the strips forming the clamping member, and a suitable nut 13 is threaded on the threaded end of the bolt and it is obvious that by turning the nut on the bolt in one direction, the clamping member 9 may be drawn tightly around the hexagonal shaped member 3 so as to prevent the accidental displacement of the clamping member therefrom. The downwardly disposed end 14 is bent into engagement with one of the sides of the nut so as to lock the same against further rotation, thus hold the bolt in its properly adjusted position and thereby insuring the proper engagement of the clamping member with the hexagonal shaped member 3.

As is clearly shown in Figure 1, the support will maintain the air retainer valve 1 in proper position on the railway car, and whenever it becomes necessary to remove the air retainer valve for cleaning or repairing purposes, the same may be easily disengaged from the clamping member 9 without ne-

cessitating the removal of the support which is adapted to provide a permanent fixture. After the valve has been cleaned or repaired, the same is replaced, and placed in the support where it is held in its proper position.

The provision of a support of the above mentioned character which is adapted for a particular purpose will save considerable time and labor in removing and attaching an air retainer valve on a railway car, and will furthermore eliminate unnecessary waste and thus minimize the expenses and cost incident to the handling of the air retainer valves on railway cars.

While I have shown the preferred embodiment of my invention, it is to be understood that minor changes in the size, shape, and arrangement of parts may be resorted to without departing from the spirit of the invention and the scope of the appended claim.

Having thus described the invention, what I claim as new and desire to secure by Letters Patent is:—

A support for an air retainer valve comprising a bracket, a clamping member formed of a strip of flexible material, the intermediate portion thereof being disposed against the outer side of the intermediate portion of the bracket, a pair of ears extending laterally from the opposite sides of the intermediate portion of said clamp strip, said ears being bent around the sides of the intermediate portion of the bracket, the free ends of said ears being disposed adjacent the inner face of the intermediate portion of the bracket and secured thereto, a bolt and nut for adjustably securing the free ends of the clamp strip together whereby the latter may be securely tightened about the valve, one of the free ends of the clamp having a reverse bend to engage the nut to prevent accidental turning of the nut on the bolt.

In testimony whereof I affix my signature.

PATRICK J. MCKEE.
